UNITED STATES PATENT OFFICE.

EMERY L. WALKER, OF MILWAUKEE, WISCONSIN, ASSIGNOR TO KIECKHEFER BOX COMPANY, OF MILWAUKEE, WISCONSIN.

PACKAGE-SEALING MACHINE.

1,270,572.

Specification of Letters Patent. Patented June 25, 1918.

Application filed January 19, 1917. Serial No. 143,255.

To all whom it may concern:

Be it known that I, EMERY L. WALKER, a citizen of the United States, residing at Milwaukee, in the county of Milwaukee and 5 State of Wisconsin, have invented a certain new and useful Improvement in Package-Sealing Machines, of which the following is a full, clear, concise, and exact description, reference being had to the accompanying 10 drawings, forming a part of this specification.

My invention relates to package sealing machines and is designed for use in connection with the sealing of the ends of paper 15 box forms. These paper box forms which are contemplated herein are made of the heavier grades of paper or card board, presser board, or corrugated stock, and are to be used as containers for materials having 20 a substantial weight. Consequently these boxes must be of strong material and it is generally imperative that end flaps be pressed tightly together at their abutting edges prior to the sealing operation so that 25 the box end is substantially closed.

In practice, the sealing machines are placed in shipping rooms where the containers are used and these containers or boxes are delivered to the shipping room so constructed 30 that they form four sided figures which are collapsible, thus to save space during transit and shipment. The first operation on these collapsed box forms is to open them up, press the end flaps into position at one end 35 of the box and seal the end flaps. The box is then ready to be filled. If the sealing of one end would have to be done at the factory where the boxes were made, then of course an enormous amount of space would 40 be required to ship these containers. For this reason the desirability of shipping these containers with the four sides in such condition that they can be collapsed is apparent. In the shipping rooms, of course, non-skilled 45 labor is used to form and seal the ends of these boxes.

My invention consists in the provision of a simple sealing machine using a pair of platens so designed that unskilled labor can 50 be utilized for sealing the box ends. It is necessary during this sealing operation, as before stated, to press the end flaps toward each other, and the object of my invention is to provide a platen structure so that manual manipulation of these end flaps is pos-

sible to press them together just prior to the sealing operation.

I will describe my invention more in detail by referring to the accompanying drawings illustrating the same, in which: 60

Figure 1 is a front view of a machine constructed in accordance with my invention;

Fig. 2 is a side view partly in section of the machine shown in Fig. 1;

Fig. 3 is a top view of the platen structure; 65

Fig. 4 is a modified form thereof; and

Fig. 5 is a perspective view partly broken away to illustrate the platen operating mechanism. 70

My improved machine contemplates a framework having the struts 1 united by stringers 2, thus to form a rectangular structure, which structure is supported upon suitable legs 3. Cross pieces 4 are provided 75 at the top and extend between the stringers 2, these cross pieces supporting vertically arranged bearings 5, 5. These vertically arranged bearings carry slidably mounted stems 6, which stems carry platens 7 at their lower extremity. Suitable springs 8 tend to hold these platens together with their stems in an upward position, such for instance, as shown at the two opposite extremities of Fig. 1. In order to move the plunger and the platen 7 downwardly I provide a cam fixedly mounted upon a stem 10, which stem is secured between fingers 11, 11 extending upwardly from the bearings 5. 80 A suitable handle 12 fixedly secured to the cam may be used to rotate the cam. This cam engages the upper extremity of the spindle 6, and thus when the handle 12 (Fig. 2) is moved in a contra-clockwise direction, the spindle and hence its connected platen is 85 moved downwardly. The arrangement of the cam and spindle is such that when the platen has been moved downwardly at or near its limiting position the cam locks the structure in that position so as to hold it in 90 place. There is secured to the cam also a crank arm 13, which crank arm through the agency of the link 14 may be operated by the foot pedal 15. This pedal is pivoted upon a bracket 16 extending downwardly 95 from the framework of the machine and engages a second link 17, which link 17 is interposed between the link 14 and the foot lever 15. Thus when the foot lever 15 of Fig. 2 is moved from its upward position 100

110

contra-clockwise to its lower position, the cam 9 and handle 12 corresponding thereto are also moved in a contra-clockwise direction. Thus the platen 7 can be moved downwardly either through the agency of the handle 12 or the foot lever 15. When the platen is to be released and permitted to move into its upper position the handle 12 preferably is used. The platen 7 co-operates with another platen 18, this platen being carried upon a stem 19. The stem of this platen is pivotally mounted upon a spindle 20 supported in cross pieces 21 secured to the framework of the machine. A stop 22 is provided upon the stem 19 to limit its forward tilting movement as is apparent from the illustration of Fig. 2, and a spring catch 23 holds the stem 19 normally in its vertical position. This spring pressed pin 23 operates with the notch 24 in such manner that merely the pull exerted upon the platen 18 to move it in a contra-clockwise direction is sufficient to release this pin from the notch 24. This spring pressed pin thus merely serves as a yielding holding means for the stem and plunger. The stem 19 also has at its lower extremity a framework 25 adapted to support the lower unfolded extremities of a box form 26 when same is placed over the platen 18.

It will be noted that the upper platen 7, as more clearly apparent from Fig. 3, is smaller in size than the outer outline of the box form, the purpose of which will presently appear. In the normal operation of the machine the box form with both ends unfolded is placed over the platen 18, which platen at that particular time is tilted forwardly toward the operator. The framework 25 limits the downward movement of this box form. Thereupon, the loose box ends are folded over, the edges of the platen 18 serving to control the bending along a straight line. After the box flaps have been folded and adhesive is applied, the stem 19 is swung backwardly into its vertical position, whereupon the operator through the use of his hands presses the end flaps of the box together as shown in Fig. 3, at the same time operating the foot lever 15 to bring the upper platen downwardly and seal the box end flaps together. The cam 9 locks the platens together so that the sealing action may take place, during which time the operator passes to the next unit of the machine and duplicates his actions. He then passes on to the next unit, and so on, finally coming back to the first unit where the adhesive has set. Then through the agency of the handle 12 he releases the platen 7, swings the stem 19 toward himself and removes the box whose one end by that time is completely closed and sealed.

It is important, of course, that the outer box end flaps have their meeting edges abut.

This is ordinarily impossible when such heavy material is used as contemplated for in this machine. Consequently manual manipulation of the end flaps serves the purpose of holding them together into their abutting condition while the upper platen is coming down into sealing position. For this reason the upper platen must have certain portions of its edge fail to extend outwardly to the outer outline of the box form as placed upon the lower platen.

In Fig. 4, I have shown a modified form of platen 7^a which has the cut-away portion 27 to permit proper use of the hands during the operation of placing the flaps together. The meeting line of the flaps both in Figs. 3 and 4 is shown at 24'.

From what has been described the nature of my invention will be clear to those skilled in the art.

Having however thus described one form which my invention may take, what I claim as new and desire to secure by Letters Patent is:

1. In a box end sealing machine the combination with a pair of relatively movable platens, a supporting structure therefor whereby relative motion may be imparted to the platens so that a box form may be placed upon one of said platens without interference from the other platen, means for moving and locking one of said platens whereby said platens are adapted to seal the overlapping ends of a box structure placed therebetween by pressing the overlapping ends between them, one of said platens being within the box form and the other platen without, the outer configuration of said latter platen being such as to permit a portion of the folded end of the box form to remain exposed for purposes of manual manipulation of the end flaps of said box form during the time the platens are being moved into their limiting sealing position.

2. In a box end sealing machine the combination with a pair of relatively movable platens, a supporting structure therefor whereby relative motion may be imparted to the platens so that a box form may be placed upon one of said platens without interference from the other platen, means for moving and locking one of said platens whereby said platens are adapted to seal the overlapping ends of a box structure placed therebetween by pressing the overlapping ends between them, one of said platens being within the box form and the other platen without, the outer configuration of said latter platen being such as to permit a portion of the folded end of the box form to remain exposed for purposes of manual manipulation of the end flaps of said box form during the time the platens are being moved into their sealing position, the said platen which is adapted to be within

the box form having edge portions substantially parallel to the sides of the box form to permit folding of the box flaps into their limiting sealing position.

- 5 3. In a box end sealing machine the combination with a pair of relatively movable platens, a supporting structure therefor whereby relative motion may be imparted to the platens so that a box form may be
10 placed upon one of said platens without interference from the other platen, means for moving and locking one of said platens whereby said platens are adapted to seal the overlapping ends of a box structure
15 placed therebetween by pressing the overlapping ends between them, one of said platens being within the box form and the other platen without, the outer configuration of said latter platen being such as to permit a
20 portion of the folded end of the box form

to remain exposed for purposes of manual manipulation of the end flaps of said box form during the time the platens are being moved into their sealing position, the said platen which is adapted to be within the box 25 form having edge portions substantially parallel to the sides of the box form to permit folding of the box flaps into their limiting sealing position, said outer platen having cut-away portions to accommodate the fingers when pressing the said overlapping ends together.

In witness whereof, I hereunto subscribe my name this 24th day of November A. D. 1916.

EMERY L. WALKER.
